CLAIM

The ornamental design for a tilt truck, as shown and described,

DESCRIPTION

FIG. 1 is a perspective view of a tilt truck showing my new design;

FIG. 2 is a right side elevational view of the tilt truck of FIG. 1, the left side elevational view of the tilt truck being a mirror image thereof;

FIG. 3 is a front elevational view of the tilt truck of FIG. 1; FIG. 4 is a rear elevational view of the tilt truck of FIG. 1; FIG. 5 is a top plan view of the tilt truck of FIG. 1; and, FIG. 6 is a bottom plan view of the tilt truck of FIG. 1.

The broken line showing in the Figures of the wheels, the casters, the frame, and the handle is for illustrative purposes only and forms no part of the claimed design.
